UNITED STATES PATENT OFFICE.

WILLIAM H. SANDERS, OF BEDFORD HILLS, NEW YORK.

COMBINATION-PADLOCK.

1,219,490.

Specification of Letters Patent. Patented Mar. 20, 1917.

Application filed April 23, 1915. Serial No. 23,479.

To all whom it may concern:

Be it known that I, WILLIAM H. SANDERS, a citizen of the United States, residing at Bedford Hills, in the county of Westchester, State of New York, have invented certain new and useful Improvements in Combination-Padlocks; and I do hereby declare the following to be a full, clear, and exact description of the invention, such as will enable others skilled in the art to which it appertains to make and use the same.

This invention relates to new and useful improvements in locks, and is particularly directed to the provision of a permutation lock provided with means for changing the combination of the lock.

One important object of the invention is to improve and simplify the general construction of devices of this character.

20 A second important object of the invention is to provide an improved and simplified device of this character wherein the combination may be changed by the user when desired.

25 With the above and other objects and advantages in view, the invention resides more particularly in the novel combination, formation and arrangement of parts as more fully described and pointed out in 30 the appended claim.

Reference is had to the accompanying drawings, wherein similar characters of reference designate the corresponding parts throughout the several views, and in which:

35 Fig. 1 is a front view of the lock.

Fig. 2 is a rear view thereof with the back plate removed.

40 Fig. 3 is a sectional view taken vertically through the lock on the line 3—3 of Fig. 2, the back plate being shown in place in this view.

Fig. 4 is a sectional view taken horizontally on the line 4—4 of Fig. 2 and showing the back plate in place.

45 Fig. 5 is a perspective view of the back plate.

Fig. 6 is a perspective view of the tumbler shaft and certain parts connected thereto detached from the lock casing.

50 Fig. 7 is a perspective view of one of the tumblers, and

Fig. 8 is a perspective view of the back plate holding member.

Referring now more particularly to the 55 accompanying drawings, the casing of the lock is shown as comprising the front wall

5, the sides 6, the top 7, and the bottom 8 which is relatively wide to accommodate the holding means for the detachable back plate 9. This back plate has its top portion beveled, and is provided with a beveled tenon 10, and the top 7 is extended, and has the under face of said extended portion beveled and provided with a recess at 11 to receive the tenon of the back plate whereby the 65 upper portion of the back plate may be held against displacement. To hold the lower portion of the back plate against displacement laterally and relieve strain on the holding means to be described, the bottom 70 8 of the lock is provided with a projection 12 which seats in a recess 13 in the back plate.

The tumbler mechanism for the lock comprises a plurality of telescoping shaft sections 14. The outermost of which is journaled in an opening 15 in the front wall of the lock. Inwardly of the wall the shafts are successively extended one past the other to provide free peripheral portions and 80 these portions are squared or otherwise provided with regular series of faces 16 to operatively engage each a respective tumbler member. Outwardly of the wall the shafts are enlarged, the outer portions successively 85 extended one past the other, and the free portions thus provided carry a series of indicator plates 17. Each of the tumbler members comprises a disk 18 having its peripheral portion cut away at 19 at one side to release the shackle member as will be described and provided with a central opening 20 to seat on one of the portions 16 of its respective shafts. The tumblers are held in place on the shafts by a disk or washer 21 secured to the end of the innermost shaft by a screw 22. To hold the outermost shaft against displacement from the casing, a disk 23 is secured thereon by means of pins 24 engaged in the shoulders formed by 100 squaring the shaft inwardly of the front wall. The indicator plates 17 carry series of symbols 25, and the portions 16 of the shafts, which in this instance are square carry corresponding symbols 26, there being 105 relatively more symbols on the plates 17 which thus serve as dummies. The numbers on the plates 17 are so correlated with the numbers on the squared members 16 that when one of the tumblers 18 is placed on 110 a squared member 16 with the portion 19 opposite a number on said squared member the

same number will appear opposite an index, indicated to the left of the plate 17 in Fig. 1, said tumbler 18 is in position to release the shackle, that is to say is in vertical position. Thus there will be four numbers to which each of the tumblers 18 may be set and it is obvious that in place of having squared members 16 the members may be made of any desired polygonal contour so as to increase the number of combinations that may be made. Thus with any given setting in the construction shown there will be one number on each plate which is an operative number while the remainder will be dummies and there are four numbers on each plate which may be made operative numbers by properly shifting the position of the respective tumbler 18.

The lock is provided with a usual shackle 27 which has its arms extended through the top 7 of the casing. That arm adjacent the tumbler mechanism being relatively shorter, and being provided with an arcuate cut away portion 28 for receiving the peripheral portions of the tumblers, this arm being spaced from the axis of the tumblers, a sufficient distance so that when the cutaway portions 19 thereof are aligned and disposed opposite the said arm, the shackle may be drawn to move the arm outwardly of the casing to thus unlock the lock. The other arm 29 of the shackle is extended into a cutaway portion 30 formed in one end of the bottom 8, and is adapted to be engaged in a strap member 31 carried by the back plate 9 and adapted to extend in said recess.

Thus the back plate is held against removal except when the shackle is in an unlocked position. To further hold this back plate so that it will not become displaced except when desired to remove it, a recess 32 is provided in the bottom 8 and the bottom

is further provided with a bore 33 communicating with the recess. Slidably positioned in the recess is a keeper block 34 having a slot 35 formed in its under portion to receive a strap member 36 carried by the back plate, the block being normally urged to such holding position by a leaf spring 37 secured on the bottom and bearing thereagainst. The block is manipulated by a button member 38 formed thereon, and extending outwardly of the casing through the bore 33.

From the foregoing it is seen that an exceedingly simple structure has been provided which will efficiently perform all of the functions set forth. To change the combination of the lock, the shackle is drawn to inoperative position and the button 38 pressed so that the back plate may be removed. Ready access is thus had to the tumbler mechanism, and this is changed by unscrewing the screw 22 and removing the tumblers to replace them differently on the shafts.

What is claimed is:

A lock of the class described comprising a casing, the top of the casing being extended and beveled and provided with a recess, a detachable back portion having its top beveled, a tenon thereon engaging in the recess, a shackle, permutation mechanism for said shackle, a member carried by the back portion and engageable by the shackle, a second member carried by the back portion, and a keeper block in the casing for engaging said second member.

In testimony whereof, I affix my signature, in the presence of two witnesses.

WILLIAM H. SANDERS.
